Raymond N. Coates, 204 Grove Way, Hayward, Calif.

Filed Feb. 8, 1960, Ser. No. 59,301

Term of patent 14 years

(Cl. D91—4)

FIG. 1.

FIG. 2.

FIG. 3.

The dominant features of my design reside in the full line portions of the drawing.

I claim:

The ornamental design for an ornamental water fountain, substantially as shown and described.
